Chas. E. Townsend

ATTORNEY

UNITED STATES PATENT OFFICE.

CHARLES ALLEN, OF EL PASO, TEXAS.

AUTOMATIC SAND-TRAP.

1,374,626.

Specification of Letters Patent. Patented Apr. 12, 1921.

Application filed April 28, 1920. Serial No. 377,345.

To all whom it may concern:

Be it known that I, CHARLES ALLEN, a citizen of the United States, residing at El Paso, in the county of El Paso and State of 5 Texas, have invented a new and useful Improvement in Automatic Sand-Traps, of which the following is a specification.

This invention relates to automatic devices for separating suspensions into two 10 products and is more especially concerned with the separation of sand from water for dam building and like purposes.

The object of this invention is to provide a simple and inexpensive device for carrying 15 on the separation automatically, such device embodying a minimum number of operating parts and being of rugged construction and not likely to get out of order.

The present structure includes a tank or 20 cone having an overflow for the discharge of the light and slowly settling particles and a bottom discharge orifice for the discharge of heavy and more quickly settling particles. The tank is suspended from an overhead 25 support by means of springs arranged at three points and a valve is provided for the bottom discharge orifice, said valve being carried in fixed position. When a sufficient quantity of solids have accumulated in the 30 bottom of the tank, the springs are compressed allowing the tank to move downwardly thereby unseating the valve, whereupon the sand will be discharged through the bottom orifice. These springs may be 35 regulated to provide for different degrees of density in the product discharged from the bottom orifice. The hanger for the springs is preferably carried by the launder as is also the valve stem. In this way I am 40 enabled to do away with separate supporting frames.

One form which my invention may assume is exemplified in the following description and illustrated in the accompanying 45 drawing, in which—

Figure 1 shows a vertical central sectional view of the device embodying my invention.

Fig. 2 shows a plan view of the same. 50 Referring more in detail to the accompanying drawing, I show a tank 10 preferably cone-shaped and provided with a discharge orifice 11 at the bottom thereof into which is seated a valve 12 carried by a 55 stem 13. The tank is provided with flanges or brackets 14 near its top to rest upon com-

pressible coil springs 15, there being three such springs. These springs 15 are suspended from a hanger 16 in the form of a spider, said hanger being bolted to a 60 launder 17. The valve stem 13 extends upwardly through the tank and passes through an opening in the spider and is in turn connected to the launder 17 by means of a fastening device 18.

The launder is provided with a pipe 19 discharging into the tank and said tank has an overflow spout 20 for the discharge of light and slowly settling particles. The material to be treated is fed into the tank continuously and normally the tank is elevated by means of the springs so that the valve 12 is seated and closes the discharge orifice 11. Thereafter, when a sufficient quantity of heavy and quickly settling solids 75 accumulate in the bottom of the tank, the tank is moved downwardly by the weight thereof resulting in the unseating of the valve and permitting the settled material to escape. If the solids be discharged faster than they 80 are accumulated, then the tank becomes lighter and the springs will expand to raise the tank and close the discharge orifice.

The present device, it will be noted, is supported from a spider which is fastened 85 directly to the launder from which the feed stream is received. The tank has a three-point suspension which insures a continuous bearing on all points. The device is not likely to get out of order on account of the 90 fact that the valve rod and the discharge orifice cannot get out of line. The spring suspension insures an opening of the discharge orifice proportionate to the weight, whereas counterbalancing weights such as 95 have been used hitherto result in a wide opening of the discharge orifice after the critical point is passed. The springs here shown may be adjusted or regulated to provide for varying degrees of density in the 100 discharge product by manipulation of the nuts on the bolts 21 which support the springs.

Various changes in the construction and arrangement of the several parts may be employed without departing from the spirit of my invention as disclosed in the appended claims.

Having thus described my invention, what I claim and desire to secure by Letters 110 Patent is:

1. An automatic separator of the type men-

tioned, comprising a tank having an overflow and a bottom discharge orifice, a hanger, springs carried by the hanger at three points, flanges at the sides and top of the tank resting upon said springs to support the tank, a valve carried on a fixed support and normally closing the discharge orifice, whereby the accumulation of solids in the tank causes the latter to be moved downwardly compressing the springs and thereby unseating the valve and means for adjusting said springs to vary the operation of the tank and valve.

2. An automatic separator of the type mentioned, comprising a launder, a spider fixed to the launder, compressible coil springs carried by said spider, a tank suspended from the spider by means of said springs, said tank embodying an overflow and bottom discharge orifice, and a valve for the bottom discharge orifice normally closing the same and being carried upon a fixed support whereby when a sufficient quantity of solids accumulate in the tank, the latter will move downwardly compressing the springs and unseating the valve and means for adjusting said springs to vary the operation of the tank and valve.

3. An automatic separator of the type mentioned, comprising a launder, a tank having an overflow and a bottom discharge orifice, a spider carried by the launder, springs suspending the tank from the spider at three points, and a valve for the bottom discharge orifice normally closing the same and carried fixedly by the launder.

4. An automatic separator of the type mentioned, comprising a launder, a tank having an overflow and a bottom discharge orifice, a spider carried by the launder, springs suspending the tank from the spider at three points, and a valve for the bottom discharge orifice normally closing the same and carried fixedly by the launder, said valve being provided with a stem extending upwardly through the tank and passing through an opening in the spider.

In testimony whereof I have hereunto set my hand in the presence of two subscribing witnesses.

CHARLES ALLEN.
